UNITED STATES PATENT OFFICE.

EDWARD B. ROHMER AND LOUIS C. MUELLER, OF TOLEDO, OHIO.

AUTOMATIC TICKET STAMPING AND RECORDING MACHINE.

Application filed March 13, 1922. Serial No. 543,174.

To all whom it may concern:

Be it known that we, EDWARD B. ROHMER and LOUIS C. MUELLER, citizens of the United States, and residents of Toledo, in the county of Lucas and State of Ohio, have made an Invention Appertaining to Automatic Ticket Stamping and Recording Machines; and we do hereby declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to stamping and recording mechanisms, and is particularly intended for use by persons selling railroad and other tickets.

In the sale of such tickets the company for which the ticket salesman is working has no way of checking up to ascertain the amount for which tickets are sold other than to know that it is receiving an amount which will cover in an aggregate the amount which should have been received for all of the tickets sold. In other words, a clerk can ask a customer any price within reason for a ticket, and particularly a transportation ticket, and if the customer does not know the exact price of the ticket he can be easily overcharged for the same and this is frequently done by dishonest clerks and the extra amount appropriated by him.

The primary object of this invention is the provision of a machine, more particularly intended for use in connection with the sale of transportation tickets, which machine is easily and quickly operable to stamp a ticket with the price thereof and, in addition thereto, with other data, such, for instance, as the date of sale, serial number of the sale, station at which sold and the number of the clerk selling the same, and which in addition to stamping the ticket with such data will record certain data with respect to the ticket sale, as for instance, the serial number of the sale and the price for which sold, for use by the auditor of the company or others in checking up the clerk

selling the ticket. This provides a double check for the local bookkeeper and affords protection for the clerk making the sale.

A further object of the invention is the provision in a machine of this character, of a repeat mechanism, which is operable by the clerk to permit a repeating of the stamping on successive tickets sold except that the serial number of the sale is successively changed for each ticket stamped, thus enabling a plurality of tickets sold for the same price to be successively stamped by the machine without resetting the machine for each ticket.

A further object of the invention is the provision of simple and efficient mechanism which is operable to permit a repeated stamping of the same data on different parts of the same ticket, as in the case of stamping different portions of an interline ticket, the sales number and also, preferably, the recording mechanism being rendered inoperative by such means. Other objects and advantages of the invention will be apparent from the following detailed description thereof.

The invention is fully described in the following specification, and while, in its broader aspect, it is capable of embodiment in numerous forms, a preferred embodiment thereof is illustrated in the accompanying drawings, in which,

Figure 1 is a plan view of a machine embodying the invention. Fig. 2 is a right side elevation of the machine with the casting removed and with parts broken away. Fig. 3 is an enlarged fragmentary detail of the locking mechanism for the price keys. Fig. 4 is a perspective view of the month wheel of the dating mechanism. Fig. 5 is an elevation of the left side of the machine with the case removed. Fig. 6 is an enlarged central vertical fragmentary section on the line 6—6 in Fig. 5. Fig. 7 is an enlarged fragmentary side view of a portion of the date stamping mechanism with a portion of the same and the enclosing case partly broken away. Fig. 8 is a perspective view of one of the date printing wheels. Fig. 8^a is a perspective view of one of the price printing segments. Fig. 9 is a longitudinal

vertical section taken substantially on the line 9—9 in Fig. 20. Fig. 10 is a back view of a ticket stamped by the machine. Figs. 11 and 12 are enlarged end and top views respectively of the removable die plate. Fig. 13 is a longitudinal vertical section taken substantially on the line 13—13 in Fig. 20, with parts broken away. Fig. 14 is an enlarged fragmentary section similar to Fig. 13 of the rear inking ribbon feeding mechanism. Fig. 15 is an enlarged fragmentary section on the line 15—15 in Fig. 13, with parts broken away. Fig. 16 is a longitudinal vertical section on substantially the line 16—16 in Fig. 20, with parts broken away and some parts removed and with the operating parts shown in normal position. Fig. 17 is a fragmentary side elevation of a portion of the interline mechanism with the initial position thereof, upon a depression of the interline key, shown in dotted lines. Fig. 18 is a similar view showing in full lines the position of the parts after a depression of the interline key and before the operating lever has been moved forward, and showing in dotted lines the relative position of the parts when the operating lever is in forward position. Fig. 19 is a similar view showing in full line the position of the parts indicated by dotted lines in Fig. 18, and showing, in dotted lines, the position of the parts after the return of the operating handle to normal position. Fig. 20 is a cross-section on the line 20—20 in Fig. 2 together with the enclosing case of the machine. Figs. 21 and 22 are continuing sections, respectively, of the forward and rear portions of the machine taken substantially along the line 21—22 in Fig. 2, together with the enclosing case. Fig. 23 is an enlarged longitudinal vertical section of the front ribbon feeding mechanism taken between the machine frame plates 3 and 4 looking toward the right, and close to the former, with parts broken away. Fig. 24 is a similar section of the front inking ribbon feeding mechanism taken substantially on the line 24—24 in Fig. 21, with parts broken away, and Fig. 25 is an enlarged fragmentary section on the line 25—25 in Fig. 13.

Referring to the drawings, 1 designates the machine base, and 2, 3, 4, 5 and 6 a plurality of plates or frame members extending longitudinally of the base and fixedly rising therefrom in transversely spaced parallel relation. A main casing body 7, with forward and rearward extensions 8 and 9, encloses the frame plates, and the body portion 7 has the top key board 10. The main operating shaft 11 of the machine is journaled in the lower portions of the frame plates transversely thereof and substantially midway of their ends and has one end projected without a side of the

casing 7 and carrying the operating crank-arm 12. A pair of spaced arms 13 rise from the shaft 11 at the outer sides of the set of frame plates and carries a rocker or cross-bar 14, which extends through slots 14' in the different frame plates to permit the cross-bar to have limited rocking movements lengthwise of the frame for the purposes hereinafter described.

Ticket stamping mechanism.

The machine, in the present instance, is provided with five sets of keys 15 spaced transversely of the machine and with the keys of each set in spaced relation longitudinally of the machine and carried for vertical reciprocating movements by a respective frame plate (2, 3, 4, 5 or 6), one set of keys being associated with each frame plate. The keys of each set are nine in number with the numeral designations thereon running from 1 to 9, the first two rows of keys to the right designating cents and the last three rows to the left designating dollars, so that an amount as high as \$999.99 or any lesser amount down to 1¢ can be printed on a ticket and recorded by the machine. Each key 15 is carried by a standard 16 which extends down through a registering opening 17 in the key board 10 at one side of the frame plate with which it is associated and has a pin 18 projecting transversely therefrom through a vertical slot 19 in the respective frame plate, which pin and slot permit the key standard to have limited vertical reciprocating movements and a slight rocking movement longitudinally of the frame plate (Fig. 20). A coiled contractile spring 20 connects each pin 18 to a stationary pin 21 fixedly carried above the same by the associated frame plate and this spring normally acts to retain the key in elevated position. When a key has been depressed it is retained in such position by a catch lug 22 (Fig. 3) on the forward edge of the opening 17 in the key board through which the key standard passes, the catch lug being tapered on its under side to permit it to pass down through the opening 17 when the key is depressed.

A lock-bar 23 is provided for each set of keys and is mounted for longitudinal reciprocating movements at the under side of the key-board 10 at one side of the associated frame plate and has an opening or notch 24 therein for each key standard 16 of the associated set, the notch or opening being of a length to permit the catch stud 22 to enter the same with the key standard. Each lock-bar 23 is held against the key-board 10 for longitudinal reciprocating movements by a plurality of transverse frame-bars 25 which extend through the upper portions of the frame plates im-

mediately beneath the key board 10. The rear end of each lock-bar 23 is connected by a coiled contractile spring 26 to a pin 27 projecting downward from the key-board 10 (Fig. 3) and acts to normally impart rearward movement to the lock-bar to hold the key standards rearward against the rearward walls of the key-board opening 17 so that when a key is depressed its catch lug 22 will be caused to engage under the lower rear edge wall of the opening and thereby lock the key in depressed position. The lock-bars 23 are retracted against the tension of the springs 26 and caused to release the key standards by mechanism hereinafter described.

A guide-bar 28 (Figs. 9 and 20) is provided for each set of key standards 16 and is secured to a side of the respective frame plates 2, 3, 4, 5 or 6 and has guide openings therethrough for the lower ends of the key standards.

A key-bar 30 (Figs. 9 and 20) is mounted below each guide-bar 28 parallel therewith at a side of the respective frame plate and is guided for longitudinal movements by straps 31 (Fig. 9) secured to the respective frame plate and guide bar 28. Each key-bar 30 has a notch 32 in its top edge in register with each key standard 16 in position for the lower end of the standard when depressed to enter a notch, the notches being progressively lengthened from the forward end of the key bar rearward. It is preferable to reduce in width the portion of each key standard which enters a notch 32. The key-bars 30 are mounted for limited longitudinal movements and each has a stud 33 projecting therefrom through a slot 34 (Figs. 2 and 5) provided in the associated frame plate parallel to the key bars. Each key-bar 30 normally stands at the limit of its rearward movement in position for each key standard when depressed to enter the forward end of the registering notch 32 so that the permissible forward movement of a key-bar from normal position when any key of the associated set is depressed is determined by the length of the key-bar notch in which the key standard is projected.

A key-bar actuating arm 35 (Figs. 2, 5, 20 and 21) projects upward from the control shaft 11 for each key-bar 30 and terminates at its upper end at the rear side of the associated key-bar stud 33 adjacent thereto so that when the arm 35 is swung forward it will impart a forward movement to the key-bar, the extent of which movement is limited as above described by the length of the key-bar notch 32 in which the lower end of a key-bar standard 16 is projected. Each stud 33 is connected to the free end of the adjacent arm 35 by a coiled contractile spring 36, which normally re-

tains the key-bar 30 retracted when the arm is retracted.

Each key-bar actuating arm 35 is loose on the control shaft 11 and is yieldingly held against the rear side of the rocker or cross-bar 14 by a coiled contractile spring 37 which is fixed at one end to the adjacent frame plate and exerts a forward pull on the arm 35 and tends to impart a forward stroke to the rocker-arm 35 when the cross-bar 14 is swung forward by an operating of the control shaft. A coiled contractile spring 38 connects each rocker-arm 13 to the adjacent frame plate and tends to return the rocker arm and associated parts to normal rearward position when the crank-arm 12 is released after an operating movement thereof.

A release bar 39 (Figs. 2, 5, 16 and 20) is mounted at a side of each frame plate (2, 3, 4, 5 or 6) immediately below the studs 18 projecting through the plate from the respective set of key standards 16 and is moved downward by a depression of any key and stud 18 of the set. Each release bar 39 is supported by a pair of parallel links 40 projecting upward and forward from pivot studs 41 on the frame plate. A catch-dog 42 projects forward from the pivoted end of the rear link 40 under a stud 43 on a side of the upper end portion of the key-bar actuating arm 35 and normally engages such stud to prevent a forward key-bar actuating movement of the arm 35. Upon a lowering of the release bar 39 by the depression of any key, the dog 42 is swung downward to released relation to the stud 43 to permit a forward movement of the arm 35. The release bar 39 is normally held elevated by one or more coiled contractile springs 44.

In order to insure a complete rearward movement of the crank arm 12 before returning to its normal forward position, one end of the cross-bar 14 has a four-armed rocker 45 (Figs. 2 and 20) mounted on one end thereof, two oppositely projecting side arms of which form catch members, one or the other of which is adapted to engage the upper toothed edge of a segmental bar 46 when the cross bar has rocking movements imparted thereto. The bar 46 is rigidly carried at the outer side of the frame plate 6. The upper arm of the rocker member 45 is connected by a coiled contractile spring 47 to a pin 48 projecting from the adjacent rocker arm 13 and tends to yieldingly hold either catch finger of the rocker member in bar engaging position, depending on which side of the rocker member axis the spring is disposed. When the cross-bar 14 is at the limit of its rearward movement, or is in its normal at rest position, the forward catch finger is disposed in neutral or inoperative position and the rear catch finger is disposed in position to engage the

bar teeth when the cross-bar is moved forward so as to prevent return of the operating parts to normal position until a complete forward stroke has been made, when 5 the downwardly extending arm or tail piece of the rocker member strikes a pin 49 at the forward end of bar 46 and effects a rocking of the member 45 to place the forward catch finger in bar engaging position 10 and the rear catch finger in neutral position, thus permitting a return of the operating parts to normal position. When the operating parts are near the limit of their rearward movement to normal position, 15 the tail-piece of the rocker member strikes a stop-pin 50 on the rear end portion of the bar 46 and effects a shifting of the rocker member to place the rear catch finger thereof in operative position preparatory for the next operating stroke.

A number of rack-bars 51 corresponding in number to the sets of keys 15, and therefore, in the present instance, five in number, are mounted side by side between the two frame 25 plates 2 and 3 below the key-bars 30 associated with said plates and in parallelism with such bars. The rack-bars are supported for relative longitudinal movements, in the present instance, on three rollers 52 spaced longitudinally thereof and mounted on suitable cross shafts. A filler member 53 is disposed between the frame plate 3 and set of rack-bars to hold the bars closely assembled with the outer bar against the 30 frame plate 2. Each rack bar is provided at each end with a set of rack teeth 54, the racks at the forward ends of the bars being in mesh with respective price segments 55, of a ticket printing set disposed at the forward end of the machine, while the rack teeth at the rear ends of the bars are in mesh with respective price segments 55 of a recording set disposed at the rear end of the machine.

45 The price segments 55 of the forward set are mounted on a cross-shaft 56 (Figs. 6 and 9), which shaft is mounted at one end in a forward extension 2^a of the frame plate 2, and at its opposite end in a plate 57, 50 which is secured to the adjacent side of the forward end portion of the frame plate 3 and forms a forward extension of such plate. The extension plate 57, together with a shimming strip 58 disposed between it and the frame plate 3, fill the space between the forward end of the plate 3 and the set of rack bars 51 to assist in guiding the movement of the bars. The recording segments 55 of the rear set are similarly mounted on a shaft 59, which is mounted at its outer end in a forward end extension 23 of the frame plate 2 and at its opposite end in a plate 60 secured to the adjacent side of a forward end extension of the frame plate 3.

65 It is thus evident that a longitudinal move-

ment of any price bar 51 will communicate predetermined corresponding rocking movements to the respective front and rear segments 55 with which engaged. Each price segment 55 has a zero at the rear end of its peripheral portion and numerals from 1 to 9 disposed in successively spaced relation from the zero mark to the forward end of the segment periphery as shown in Fig. 8^a, and a forward movement of each 70 rack bar 51 is required to operate the associated segment to place the desired numeral thereof in printing position, as hereinafter more fully described.

75 Each rack bar 51, except the one next to the plate 2, has a notch in its top edge for loosely receiving the free end of an operating lever arm 61 (Figs. 9 and 20), which extends downward from a sleeve 62 loosely mounted on a respective cross shaft 63 and having an arm 64 extending downward therefrom in position for its lower end, which is forked, to straddle a pin 65 on a side of a key-bar 30 with which the rock bar is intended to be connected. The left hand bar 51 and its key bar 30, which are disposed in side abutment with the frame plate 2, are connected by a single lever arm, designated 61^a, which depends from a cross-shaft 63 at the outer side of the plate (Fig. 95 5) and engages pins 61^b and 61^c projecting respectively from the bars 30 and 51 through slots in the frame plate.

It is thus evident that a longitudinal movement of a key bar 30 will impart a 100 corresponding movement to the associated or connected rack bar 51 through the lever connection formed by the respective lever connections 62. The sleeve 62 and shaft 63 carrying the levers 61—64 of different sets, 105 are disposed in different positions lengthwise of the machine and extend through a number of frame plate 2, 3, 4, 5 and 6 necessary to connect a key-bar 30 to its associated rack bar 51. For instance, the lever arm 64 which engages the key bar 30 associated with the frame plate 6 has its sleeve extended through the frame plates 3, 4 and 5 for free rocking movements 110 therein and the ends of its shaft 63 are 115 mounted in the outermost frame plates 2 and 6.

120 A side plate 66 (Figs. 5 and 21) is secured to the outer side of the frame plate 2 at the forward end thereof in spaced relation thereto by screws 67 and is of substantially circular form at its forward end, as are also the transversely aligned forward end extension of the frame plate 2 and the forward end of the plate 57. A set of four 125 date wheels 68 are mounted side by side between the plate extension 2^a and plate 66 adjacent to the upper edges thereof on a shaft 69, and at the outer side of the set of date wheels on the shaft therewith is 130

mounted a month wheel 70. The date wheels 68 are of gear tooth form with a naught or numeral designation on the outer end of each tooth, as shown in Fig. 8, and the month wheel has month designations arranged successively around its periphery, as shown in Fig. 4. The month wheel 70 has twelve holes 71 provided therein in equidistantly spaced relation around its center and these are adapted to be engaged by a removable pin 72 projecting through a slot 73 in the plate 66 so that a manual movement of the pin will move the month wheel to place successive month designations in printing position.

Each date wheel is engaged at its lower side by a respective toothed operating wheel 74, the innermost one of which is mounted on a shaft 75 that is journaled in 20 and projects outwardly from the plate 2 through an enlarged bearing in the plate 66 and carries a hand control wheel 76 at its outer end. Three telescoped sleeves 77 are mounted for relative rotation on the 25 shaft 75, the inner sleeve rigidly connecting the third wheel 74 to a central wheel 78, the next sleeve connecting the second wheel 74 to a control wheel 79, and the outer sleeve connecting the outer wheel 74 to a 30 control wheel 80. It is thus evident that an adjustment of any wheel and the date wheel with which it is connected may be accomplished by a turning of the respective control wheel. For instance, if it is 35 desired to stamp the date "Nov. 23, '21" on a ticket, as indicated on the ticket in Fig. 10, the month wheel 70 is moved to place the month designation "Nov." in printing position and the control wheels 40 80, 79, 78, and 76 are respectively turned to place the numerals "2," "3," "2" and "1" of the respective date wheels 68 in printing position, as best illustrated by reference to Figs. 6, 7 and 21.

45 At the left of the plate 57 are mounted three serial number wheels 81 with their upper edges disposed in printing position and horizontally aligned with the upper edges of the price segments 55 and date wheels 50 68. Each serial wheel 81 has a naught and successive numeral designations from 1 to 9 arranged around its periphery and the inner wheel or that adjacent to the plate 57, which is the unit wheel, is fixedly 55 mounted on a shaft 82, which is journaled at its inner end in the plate 57 and extends outward therefrom and is journaled at its outer end in a forward end extension 6^a of the frame plate 6. The second or tens 60 serial wheel 81 is fixed on a sleeve 83, which is mounted on the shaft 82, and the third or hundreds serial wheel 81 is fixed on a sleeve 84, which is mounted on the sleeve 83. The shaft 82 and sleeves 83 and 84 have 65 control wheels 85, 86 and 87, respectively,

fixed to their outer ends, as shown in Figs. 6 and 21, so that a turning of any control wheel will effect a turning of its respective serial wheel. The peripheries of the wheels 85, 86 and 87 are provided with designation 70 numerals the same as the serial wheels. Each serial control wheel 85 and 86 is provided with a star wheel 88 and the wheel 87 is provided with a ratchet wheel 89, which latter is engaged by a pawl 90 carried by a rocker arm 91, which is mounted for rocking movements on the sleeve 84 and has movements imparted thereto by mechanism hereinafter described. A spring 92 normally retains the pawl in engagement with 80 the teeth of the ratchet wheel. A shaft 93 is mounted at one side of the serial control wheels in the frame plate 6 and in a bracket arm 94 projecting from the forward end 85 of the frame plate 5, and a pair of star-wheels 95 is mounted on this shaft, one in mesh with the star-wheel 88 and in position to be engaged by a pin 96 on the wheel 87, and the other in position to mesh with the star wheel 88 and in position to be engaged 90 by a pin 97 on the wheel 86, so that at each revolution of the unit wheel 87 a single unit movement is imparted to the wheel 86, and that at each revolution of the wheel 86 a single unit movement is imparted to the 95 wheel 85, as is common in numbering machine constructions. A spring finger 98 (Fig. 16) is carried by the forward end of the machine frame for each star wheel 88 and coacts to resist a turning of the 100 wheel. A similar spring 99 (Fig. 7) projects from a frame part 100 for each toothed wheel 74 of the dating mechanism and coacts therewith to yieldingly resist a turning thereof.

105 A segmental guard plate 101 (Figs. 5, 7, 9 and 21) extends around the forward and bottom portions of the plates 57 and 66 and the forward end extension 2^a of the frame plate 2 which parts are preferably of curved 110 form, the guard plate terminating at its upper edge near the printing point of the segments 55, date wheels 68 and 70 and serial number wheels 81 and being of sufficient width to extend from the plate 66 past the serial wheels 81, as shown in Figs. 6 and 21. A die plate 102 (Figs. 5, 9, 11 and 12) is removably mounted on the tops of the frame extension 2^a being coextensive in width with the width of the guard plate 115 101 and having its front and rear edges preferably curved or tapered, as shown, with the curve or taper of the front edge forming a continuation of the curved upper end of the guard plate 101. This plate has web flanges 103 extending across the underside thereof in spaced relation longitudinally of the die plate, and adapted to register with and seat on the respective frame parts 2^a, 5, 7 and 66. The die plate is 120 125 130

provided in its central portion with a price opening 104 through which the price segments 55 are disposed and at one side of such opening with a date opening 105 in register with the date wheels 68 and 70 and at the other side with a serial number opening 106 in register with the serial wheels 81. The exposed or printing portions of the price segments and date and serial wheels which are exposed through the die plate openings are flush with the top portion of the die plate which is flattened and may be provided with any designating marks or data of a permanent nature which it may be desired to print on a ticket in addition to the changing designations such as the serial sales number, purchase date and amount or cost of the ticket. In the present instance a die plate in order to stamp a ticket, as noted by the ticket 107 in Fig. 10, is provided at opposite sides of the date opening 105 with the station designation, as for instance, "Union Sta." and at another side of the opening or in the space between the openings 104 and 105 with the name of the city where the ticket was issued, as for instance, "Toledo, O." The die plate may also be provided with the clerk's number designation on different portions thereof, as indicated by "#4," so that the number of the clerk issuing the ticket is noted by the stamping on the ticket. It will be understood that each clerk has his own die-plate with the proper designating number thereon which he places in the machine when he is selling tickets.

An inking ribbon 108 which extends across the top of the die plate and thence down around the guard plate 101, winds from one to another of upper and lower spools 109 and 110, which are mounted on respective stud bolts 111 projecting through the frame plates 4 and 5 and is held in shouldered engagement with one of said plates by a nut 112, threaded on the stud against the opposite side of the other plate. The free end of each stud 111 projects to the left from the plate 4 to a point without the plate 66 and carries the respective ribbon spool which is prevented from removal from the outer end of the stud by a nut 113. The feeding means for the spools will be hereinafter described.

An impression pad 115 (Figs. 1, 5 and 9) is carried over the die plate 102, normally in slightly spaced relation thereto at the forward free ends of a pair of arms 116 which extend rearwardly at the opposite sides of the frame plates 2 and 3 and are mounted at their rear ends on a cross-shaft 117 journaled in said plates, and, in the present instance, having the center rack-bar supporting roll 52 mounted thereon. A link 118 (Figs. 5, 9 and 21) is pivoted at its upper end to and extends downward from

each bar 116 intermediate its ends, and the lower ends of these links are connected by a cross-bar 119, which extends through shallow vertical slots 120 in the frame plates 2 and 3 to permit limited vertical movements 70 of the cross-bar therein. A coiled compression spring 121 (Figs. 5, 9 and 21) extends upward from each end of the cross-bar 119 and is anchored at its upper end to a pin 122 projecting from the adjacent frame plate 2 or 3, thereby tending to normally hold the links 118, bars 116 and impression pad 115 in elevated position with the cross-bar 119 in stop coaction with the upper end walls of the slots 120. The normal spacing 80 of the impression pad above the die block is sufficient to permit a free insertion of a ticket therebetween. The operating shaft 11 carries a lever arm 123 (Fig. 9) and when the control shaft is near the limit of its forward rocking movement the free end of said lever strikes the cross bar 119 and effects a lowering thereof in the slots 120, which movement imparts a downward or impression taking stroke to the impression pad 115. 90

A rocker-arm 124 (Figs. 5, 20 and 21) projects forward and downward on a slight curve from opposite ends of the shaft 117 at the outer or opposed sides of the frame plates 2 and 3 and for rocking movements 95 relative to the bars 116. These rocker arms are connected at their free ends by a cross-bar 125, which extends through shallow slots 126 in said plates, said cross-bar having a knife edge at its top side, or being of inverted V-form in cross-section, to adapt it, when raised, to engage any one of a series of V-notches 127 in the lower edge of each rack-bar 51, and thereby lock the rack-bars against movement. This locking action is 105 intended to take place after a rack-bar has been moved by an operating of the machine and thus lock the rack-bar and associated price segments 55 in adjusted positions and maintain such locking action until after the printing operations have been completed, thereby preventing any movements of the price segments during such operations. This locking movement of the arms 124 is accomplished by the cross-bar 14 when at a predetermined point in its forward movement engaging an aligned downwardly and forwardly inclined surface 128 on the lower edge of each arm so that the arms are raised as the bar 14 passes said inclines. The arms are then retained elevated or in locking position during the remainder of the forward stroke of the cross-bar 14 by reason of the bar travelling along a neutral curved lower edge portion of the arms. The inclines 128 are so disposed with respect to the movement of the cross-bar 14 that the locking movements of the arms 124 will not take place until the rack-bars have been moved to segment setting position and before the 130

printing operation. A coiled compression spring 129 extends downward from each end of the V-bar 125 and is anchored at its lower end to a pin 130 projecting from the 5 adjacent frame plate, thereby tending to normally retain the V-bar in lowered position.

Recording mechanism.

10 The mechanism for recording the prices and serial sales numbers of tickets sold is located at the rear end of the machine and the price recording means thereof includes the rearward set of price segments 55 mounted as hereinbefore described. A serial numbering mechanism identical to that of the ticket stamping mechanism is located at the right hand side of the plate 60, being shown in Fig. 22, and having like parts designated 15 20 the same as the serial numbering means previously described. A segmental inking ribbon guide plate 135 extends around the rear ends of the frame parts 2^b and 60 and has an opening 136 therein through which the 25 printing takes place, the same as through the opening in the die-plate 102 of the ticket printing mechanism. An inking ribbon 137 extends around the guide plate 135 over the opening 136 and has its upper end winding 30 on a spool 138 and its lower end winding on a spool 139 disposed respectively above and below the forward end portions of the frame parts 2^b and 60 (Fig. 9). The spools are mounted on the free end portions of 35 40 45 50 55 60 65 70 75 80 85 90 95 100 105 110 115 120 125 130 135 140 145 150 155 160 165 170 175 180 185 190 195 200 205 210 215 220 225 230 price and serial number indicating positions.

Serial number feed means.

- 5 Each serial wheel control means for both the ticket printing and recording mechanisms, disposed respectively at the forward and rear end portions of the machine, includes, as hereinafter described, a rocker 10 arm 91 carrying a pawl 90 in engagement with a ratchet wheel 89, which is directly connected to and when moved imparts movement to the unit serial control wheel 87 of the associated mechanism. The forward 15 rocker arm 91 has a link 160 (Fig. 16) projecting rearwardly therefrom and connected to the upper end of a lever 161 fulcrumed on a pin 162 fixed to the forward end of the frame plate 5. The lower end of this lever 20 is pivoted to the forward end of an operating catch bar 163 and the rear end of such catch bar is pivoted to the lower end of a lever 164 fulcrumed at a side of the plate 5 and connected at its upper end by a link 25 165 to the forward rocker arm 91. The lever 164 is disposed at the opposite side of the frame plate 5 to the catch bar 163 and is connected to the catch bar through a slot 166 in the frame plate. A coiled contractile spring 30 167 connects the upper end of the lever 161 to the frame plate 5 and acts on the lever to urge a forward pawl actuating movement to the bar 163. The catch bar 163 has a catch lug or shoulder 168 on the bottom edge 35 thereof in position to have forward engagement against the rear side of the cross-bar 14, which bar when in normal retracted inoperative position acts on the catch bar to retain it in its rearward retracted position 40 against the tension of the spring 167. Upon a forward movement of the cross-bar 114 the catch bar 163 moves forward therewith and communicates movements to both pawls 90 to impart a single unitary movement to the serial unit wheels 87 of both serial numbering mechanisms.

Recording tape operating means.

- 50 The recording tape spool 147 is mounted on a spindle 170 which is securely bolted to the frame plates 4 and 5 and projects therefrom in advance of the forward end portions of the frame plates 2 and 3 below the extension 2^b of the plate 2, the spool 55 being removably held on the spindle by a nut 171. The rear or power spool 146 of the set is mounted on a spindle 172 which is rigidly secured or clamped at one end to the forward end portions of the frame plates 60 4 and 5 and has its spool carrying portion projecting therefrom in advance of the plates 2 and 3, the spool being removably held on the spindle by a nut 173. The power spool 146 has a ratchet-wheel 174 on its 65 inner end adjacent to the frame plate 4 and

this is engaged by a pawl 175 carried by an arm 176 projecting downwardly from a hub sleeve 177 which is loosely mounted on the spindle 172 between the frame plates 4 and 5 (Figs. 16 and 22). A second arm 178 70 projects down from the hub sleeve 177 adjacent to the frame plate 5 and is connected to the rear end of a push bar 179, which is supported at its forward end for longitudinal reciprocatory movements by a screw 180 75 (Figs. 16, 21 and 22), projecting through a slot 181 in the bar. The forward end of the push bar 179 bears against the cross-bar 14, and the push bar is caused to move forward with the cross-bar 14, by reason of a 80 coiled contractile spring 182 connecting the push bar to the frame plate 5 (Fig. 16). The forward movement of the push bar is limited by the length of the slot 181 and such movement is less than the movement of 85 the cross-bar 14. It is evident that at each forward movement of the cross bar 14 the push bar 179 will be caused to follow the same by reason of the pull exerted thereon by the spring 182, thereby causing a pre-determined retraction of the pawl 175 on the ratchet wheel 174 so that upon the rearward movement of the cross bar 14 to its normal inoperative position the push bar 90 will be moved rearward thereby and impart a ratchet-wheel actuating movement to the pawl. A spring pressed detent 183 acts on the ratchet wheel 174 to prevent free turning thereof.

Inking ribbon operating mechanism.

The mechanisms for feeding the inking ribbons for both the ticket printing and recording mechanisms in first one direction and then another are substantially the same in construction and operation, and are shown in detail in Figs. 13, 14, 15, 23 and 24, and the connecting unitary operating means for the two mechanisms is shown in Fig. 13. The ribbon feeding means for the ticket printing mechanisms, which is shown in enlarged detail from opposite sides in Figs. 23 and 24, includes, as previously described, the upper and lower spools 109 and 110, respectively, which are mounted on respective studs or spindles 111 secured to and projecting to the left rigidly from the forward ends of the frame plates 4 and 5 in advance of the shortened forward end portions of the frame plates 2 and 3, with one spindle above and the other below the neck portions of the forward extension 2^a of the frame plate 2 and the associated frame plates 57 and 66. Each spool is provided at its inner end with a ratchet-wheel 185, and loosely projecting rearwardly from the spindle between the frame plates 4 and 5 is a rocker-arm 186. A bell-crank lever 187 is loosely mounted on the lower spindle 111 between the frame plates 4 and 5 and has a rear- 110 115 120 125 130

wardly projecting arm and an upwardly projecting arm, the latter being connected to an operating bar 188, which extends rearwardly therefrom and connects with the operating mechanism for the recording inking ribbon at the rear end of the machine. A spring pressed detent 189 is associated with each ratchet wheel 185 and coacts therewith to prevent a free turning thereof in either

10 direction.

The rocker arm 186 and the rearwardly projecting arm of the lever 187 are connected by a link bar 190, and this bar carries a pawl 191 at its upper end with its pivot 192 below the pivotal connection of the bar with the arm 186. A similar pawl 193 is carried by the bar 190 at its lower end with its pivot 194 below the pivotal connection 195 of the arm 187 with the bar 190. Each pawl is provided with a spring 196, which is anchored to one of the frame plates and acts to normally hold the associated pawl in engagement with its ratchet wheel. A pawl trip lever 197 is pivoted intermediate 25 its ends at 198 to the connecting bar 190 and has its opposite ends extending past the adjacent sides of the pawls 191 and 193 in position for its rear edge to engage a pin 199 projecting laterally from a tail piece of each 30 pawl. It is thus evident that when the trip lever 197 is rocked in one direction it will permit one pawl to move into engagement with its ratchet wheel and will engage the pin 199 of the other pawl and retract the 35 pawl from engagement with its ratchet wheel, and vice versa, thereby permitting only one pawl at a time to be in operating engagement with its ratchet wheel. A rocker plate 200 is carried by the trip lever 197, 40 pivotally suspended from a pivot stud 201 projecting from the lever a short distance below its fulcrum 198. The plate 200 is permitted to have limited rocking movements relative to the trip lever by reason of 45 a pin 202 projecting from the lever into a transverse slot 203 in the rocker plate. A coiled contractile spring 204 is connected at its lower end to the lower end of the plate 200 and extends upward therefrom and at 50 taches at its upper end to a stud 205 projecting from the upper end of a lever arm 206, which, in the present instance, extends above the upper end of the plate 200. This lever arm projects upward at the right side 55 of the frame plate 3 from a hub or sleeve 207 which is mounted at the rear of and below the spool 110 on a spindle 208 projecting transversely in front of the lower cut-away portions of the frame plates 2 and 3 forming 60 a bracket arm 209 (Figs. 5 and 21), which is bolted to the outer side of the frame plate 2. The hub sleeve 207 has a pair of arms 210 projecting upward and forward therefrom in spaced relation longitudinally there- 65 of and carrying a roller 211 between their

free ends in position to bear against the periphery of the ribbon spool 110. When the ribbon is winding on the lower spool 110 the different parts of the ribbon feeding mechanism will stand in the respective positions shown in Figs. 23 and 24 with the upper end of the lever arm 206 extending in advance of the trip-lever 197. As the diameter of the ribbon winding on the spool 110 increases the roller 211 is forced outward from the axis of the spool thereby causing a rearward movement of the lever arm 206. When such movement of the lever arm has been sufficient to exert through the spring 204 a rearward instead of a forward pull on the trip plate 200, the plate will have a quick movement to the rear, and the momentum of the same, as the forward end wall of its slot 203 strikes the pin 202, will cause a quick shifting of the trip-lever 197 to throw the lower pawl 193 out of engagement with its ratchet wheel and to permit the upper pawl 191 to move into feeding engagement with its ratchet wheel. The lever arm 206 is normally retained at the 90 limit of its forward movement by a coiled contractile spring 212 which extends forward from the upper end portion of the lever and is anchored at its forward end to a cross-pin 213 on the frame. 95

The rear ribbon feeding mechanism, which is illustrated in enlarged detail in Figs. 14 and 15, is the same as that above described, except that the arrangement of the parts is slightly changed. In this case 100 instead of the connecting bar 190' directly connecting the pawl carrying rocker arms, it is connected to rocker arms 214 projecting forward from the hubs of the first mentioned rocker arms, and the trip lever 197', 105 which is pivotally carried by the connecting bar 190', is connected at its upper end by a link 215 to the tail-piece of the upper pawl 191' and is connected at its lower end by a link 216 to the tail-piece of the lower pawl 193'. 110 A slight play is provided in the connections between these links and the respective pawls to permit the pawls to have limited rocking movements relative to the links without moving the same. The rear end of the operating bar 188 is connected to the lower pawl operating arm 187' through an arm 217 projecting down from the hub of said arm. A coiled contractile spring 218 connects the arm 217 to a part of the frame and 115 acts to normally impart forward movement to the operating bar. Aside from these changes the rear ribbon feeding mechanism is the same as the front mechanism. The different elements of the rear mechanism are 120 given the same designating numerals as the corresponding element of the front mechanism except that the prime mark is added thereto. 125

The control means for the operating bar 130

188 constitutes an arm 219 (Fig. 13) which is fixed to and projects up from the operating shaft 11 and has rearward coaction against a stop lug 220 on the bottom edge 5 of the control bar so that when the shaft 11 is in its normal or rearward position the control bar 188 is held at the limit of its rearward movement by the arm 219 against the tension of the spring 218. It is thus 10 evident that upon a forward movement of the operating crank 12 the operating bar 188 for the ribbon feeding mechanisms is caused to move forward under the action of the spring 218 and actuates the operating 15 pawl of the forward mechanism to impart predetermined feeding movement to its ratchet wheel, and that upon the return stroke of the bar 188 the operating pawl of the rear feeding mechanism is actuated to 20 impart predetermined rotation to its ratchet wheel.

Key release.

When a single ticket, or one requiring a 25 single stamp, is sold, it is important that the keys which were depressed preparatory to stamping a ticket be automatically released at the end of a single stamping operation and returned together with the price printing parts to normal position. As previously 30 stated, the keys are locked in depressed position by the catch-lug 24 thereof engaging under the rear edge wall of the opening in the key board 10 through which the key 35 standard 16 projects, the key being yieldingly held in this locked position by the associated lock bar 23, which is yieldingly moved rearward by the action of the spring 26. A cross shaft 225 (Fig. 9) is journaled 40 in the upper portions of the frame plates transversely thereof and has a release finger 226 fixedly projecting upward therefrom for each lock-bar 23 and in engagement therewith, whereby a forward rocking of 45 the shaft 225 and its fingers will impart a forward key releasing movement to each lock-bar 23 which is in key locking position. One end of the shaft 225 projects without 50 the frame plate 6 and carries a double armed lever 227, one arm of which projects rearward and the other forward. The rearwardly projecting arm of this lever is connected to the upper end of a vertically disposed release-bar 228, which is adapted to 55 have limited upward and forward swinging movements relative to the frame and is provided at its lower end with a nose 229 that projects rearward between a pair of guide pins 230 projecting from the outer side of 60 the plate 6 slightly in advance of the operating shaft 11. A link 231 is pivoted to and extends forward from the lower end portion of the release bar 228 and is pivoted at its front end to an upwardly and forwardly 65 extending arm 232, which is pivoted

at its lower end to a side of the frame plate 6 for free rocking movements relative thereto. A coiled contractile spring 233 is connected at one end to the rear end of the link 231 and has its other end extending rearward therefrom and anchored to the frame plate 6, thereby normally holding the release-bar 218 in the rearward position thereof shown in Fig. 2.

The operating shaft 11 has a release finger 234 projecting forward therefrom in position to trip past the nose 229 of the release bar upon a forward stroke of the operating shaft. Upon a rear stroke, however, of the operating shaft the trip finger 234 engages the bottom edge of the bar nose 229 and effects a sufficient raising of the bar to rock the fingers 226 and return the lock bars 23 to key releasing positions. As the release bar 228 moves upward the camming action 85 of its nose against the upper guide pin 230 causes a forward swinging movement of the bar to disengage the trip finger 234, after which the release parts are returned to normal position. The release bar 228 has its 90 swinging movements guided by the link 231 and rocker-arm 232.

A release key 234 is disposed at the right side of the key-board near its forward end and has its standard 235 extending down through the key-board at the outer side of the frame plate 6, the lower end portion of the key standard being provided with a longitudinally extending slot 236, which receives a guide pin 237 projecting from the frame plate 6. A coiled contractile spring 238 connects the guide pin 237 to the lower end of the key standard and acts to normally retain the key in elevated position. The release key standard has a plate 239 projecting forward from its upper end portion below the key board and at the outer side of the forwardly extending arm of the release lever 227 and is provided with a pin 240, which, upon a lowering of the release key, is intended to engage the forward arm of the release lever and impart a key releasing movement to the trip fingers 226 and key locking bars 23.

Repeat means.

Provision is made for the sale of group tickets, or a plurality of tickets, to the same destination where the price of the several tickets is the same, but the serial sales number for the successive tickets sold changes. This is accomplished by depressing a key 241 (Figs. 1 and 2), which is disposed at the outer side of the frame plate 6 in advance of the release key 234 and has its standard extending down through the key board 10 and provided near its lower end with a longitudinally extending slot 242 for receiving a guide pin 243 projecting from the plate 6. A coiled contractile spring 244 115

connects the pin 243 to the lower end of the key standard and acts to normally retain the key in elevated position. The repeat key standard has a pin 245 projecting therefrom in position to adapt it when lowered by a depression of the repeat key, to engage the top of the key release mechanism link 231 and impart a sufficient forward rocking movement to such link to withdraw the nose 229 of the release bar 228 from engaging relation to the trip fingers 234. The repeat key is locked in lowered position by the end of the spring pressed dog 246 engaging over a pin 247 on the repeat key standard. The dog 246 has a tail-piece extending rearward from its upper end in position to be engaged by the lower edge of the release key plate 239 and operated to release the lock pin 247 when the release key is depressed, thereby permitting the repeat key and release parts to be returned to their normal positions.

Interline means.

In selling interline tickets, which are provided with a plurality of sections or parts to be separately stamped, it is important that the stamping remain the same for the different parts and that the serial sales number as well as the prices for the different stampings on the same ticket remain unchanged. This is accomplished by mechanism shown in Figs. 2, 16, 17, 18, 19 and 21 and is controlled by the depression of a key 250 shown in Figs. 1 and 2. This key is located in the present instance in advance of the repeat key 241 and has its standard extended down through the key board at the outer side of the frame plate 6 and provided with a pin 251 with which a spring pressed dog 252 is adapted to engage to retain the key in depressed position. The dog 252 is moved to release the key upon a depression of the release key 234, the forward end of the plate 239 of which is disposed to engage the tail-piece of the dog when the release key is depressed. The interline key standard has a pin 253 projecting therefrom in position to engage the link 231 and move the release bar 228 to release position when the key is depressed, in the same manner as described in connection with the repeat key pin 245.

The lower end of the interline key standard is pivoted to an upwardly and rearwardly projecting rocker arm 254 which is fixedly mounted on a rock-shaft 255 projecting through and journaled in the frame plate 6. The inner end of this shaft has a rocker arm 256 (Figs. 16, 17, 18, 19 and 21) projecting rearward therefrom substantially parallel to the arm 254 and connected by a coiled contractile spring 257 to a pin projecting from the frame plate 6 above the arm. This spring acts to normally retain the rocker

arms 254 and 256 and the interline key in elevated positions. A bar 258 is pivoted at its forward end portion to and projects rearward slightly on an upward incline from the rocker arm 256 under the cross rocker

bar 14 and slidingly rests at its rear end on a cross pin 259 connecting the frame plates 5 and 6. A substantially L-shaped cam finger 260 is pivoted at one end to the bar 258 in advance of the slot 14' in which the rock-

er-bar 14 rocks and projects upward to a point above said slot and then rearward on an upward incline over the slot. The pivoted end of this finger is provided with a shoulder which rests on a pin 261 on the bar 258 and limits the relative rocking movements of the bar and finger toward each other. The rear or free ends of the bar 258 and finger 260 are yieldingly tied together by a coiled contractile spring 262.

The portion of the finger 260 which is disposed over the path of rocking movements of the cross bar 14 is provided on its lower edge at a predetermined point intermediate the ends of the slot 14' with a downwardly

and forwardly extending cam surface 263, which, when the bar 258 and finger 260 are in normal relation and the forward end of the bar is lowered by a downward rocking

of the arm 256, stands in the path of forward movement of the cross-bar 14 so that an engagement of the cam surface by the cross-bar causes an upward rocking movement of the finger relative to its carrying bar. The finger is retained in such elevated position until the cross-bar 14 has again moved rearward past the cam surface, or the interline key has been released to permit a raising of the rocker arm 256. The lowered

position of the rocker arm 256 and connected parts is shown in dotted lines in Fig. 17 and in full lines in Figs. 18 and 19, and the elevated position of the cam finger 260 with respect to its lowered carrying bar 258 is

illustrated in dotted lines in Fig. 18. The rear end of the bar 258 is prevented from raising with the cam finger by reason of a pin 264 on the catch bar 163 of the serial

number operating mechanism, which at this period in an operation is moved forward sufficiently, by reason of its forward movement with the cross-bar 14, to place said pin over the upper rear edge portion of the bar 258 in coaction therewith, as shown by the

dotted position of the pin in Fig. 18 and by the full line position thereof in Fig. 19. It will be understood that the forward movement of the bar 163 is only during the initial portion of the forward movement of the cross-bar 14. The cam 260 is provided

near its free end with a laterally projecting pin 265 which normally bears against the rearwardly turned hooked nose or free end portion of a catch-arm 266, which is pivotally suspended from a stud 267 projecting

130

from the frame 6 through the associated key guide bar 28. A spring 268 acts to hold the nose of the arm 266 against the pin 265 and to swing the arm rearward to place its hooked nose under the pin 265 in supporting engagement therewith when the cam finger is raised sufficiently for such purpose, which latter is accomplished by the upward camming movement of the finger as shown 10 by dotted lines in Fig. 18 and by full lines in Fig. 19.

The cross-bar 14, during its initial forward stroke after a setting or depression of the interline key 250, causes an upward camming of the cam finger 260 to permit its pin 265 to engage over and be supported by the hooked end of the catch arm 266, as above stated, and during such initial stroke of the cross arm the catch bar 163 is permitted 20 to move forward and impart an indexing movement to the serial numbering mechanisms, and at the same time to move its pin 264 and the rear end of the bar 258 to positively hold such bar in depressed position. During a rear stroke of the cross-bar 14 it engages the catch shoulder of the feed bar 163 and forces the bar rearward to its normal position, thereby moving the pin 264 rearward out of locking 30 engagement with the bar 258 and permitting said bar to move upward under the tension of the spring 262 so that it then stands with its rear end in register with the path of movement of the pin 264, as 35 shown by dotted lines in Fig. 19, to prevent any subsequent serial number indexing movement of the feed bar 163 until the interline key has been released. The rear end of bar 258 is disposed under the catch 40 bar 153 of the recording mechanism adjacent thereto so that when the bar 258 is raised from its normal position its rear end strikes the bar 153 and raises it sufficiently to prevent the actuating arm 156 when 45 moved forward from engaging the catch lug 158 of the bar 153, thereby permitting the recording mechanism parts actuated by a movement of the bar 153 to remain at rest. The bar 258 is normally held down 50 by a spring 269.

A link 270 (Fig. 16) extends forward from the catch arm 266 and is pivotally connected at its forward end to a rocker arm 271 depending from a rock shaft 272, 55 which is journaled in and extends through the frame plate 6 and fixedly carries the lock dog 252 at its outer end. A spring 273 acts on the rocker arm 271 to normally hold it at the limit of its rearward movement with the dog 252 in locking engagement with its pin 251. A pin-and-slot connection is provided between the catch-arm 266 and bar 270 to permit the arm to have limited rocking movements relative to the 60 bar. A forward movement of the bar 270

when the catch arm 266 is in catch engagement with the pin 265 causes a forward movement of the catch arm to release the pin and permit the catch arm 260 and bar 258 to lower to normal position. It is thus 70 evident that when the repeated stamping of an interline ticket has been completed, a depression of the release key 234 will cause its plate 239 to trip the dog 252, thereby releasing the interline key 250 to permit 75 its return to normal position, and will also communicate a forward movement to the link 270 through the shaft 272 and rocker arm 271 to withdraw the catch arm 266 from catch engagement with the pin 265, so that 80 different parts of the previously set interline mechanism are permitted to return to normal position.

General operation.

In the use of the machine it will be understood that each day, or whenever it is desired to change the date of the stamping means, the date mechanism of the machine is changed by a manipulation of the four control wheels 76, 78, 79 and 80, which control the numeral wheels 68 of the date mechanism, and the month wheel 70 is changed by movements of the control pin 72, which is permitted to have limited 95 transverse movements in the frame slot 78 and may be placed in engagement with successive holes 71 in the wheel. It will also be understood that each clerk has an individual die-plate 102 with his number or 100 other designating mark thereon, which in the present case is "4." The die-plate may have any other designating data thereon to adapt it to cooperate with the date wheels 68 and 70, price segments 55 and serial 105 number wheels 81 to impart the desired stamping on a ticket. The clerk in selling a ticket depresses the proper price keys 15 corresponding to the price of the ticket sold so as to place the proper price segments in 110 position to expose in printing position the numeral designations thereon corresponding to the ticket price, as for instance \$43.21.

Upon the depression of each key its catch lug 22 passes through the respective key board opening 17 and is moved rearward into locking engagement with the lower forward edge wall of the opening by the rearward movement of the associated lock bar 23, which movement of the lock bar is actuated by the spring 26. The lower end of a depressed key standard enters a registering notch 32 in the respective key-bar 30 and the pin 18, projecting from a side of the key standard, acts on the release bar 39 to effect a lowering of such bar and thereby impart a downward movement to the connected dog 42 to lower its hooked end from catch engagement with the stud 43 on the associated key bar actuating arm 35. The clerk hav- 115 120 125 130 135 140 145 150 155 160 165 170 175 180 185 190

ing previously placed the ticket to be stamped between the die plate 102 and impression pad 115, then moves the operating crank arm 12 forward to the limit of its stroke, thereby imparting a forward rocking movement to the cross-bar 14, which in turn permits a forward stroke of each release arm 35 so that the actuating spring 37 connected thereto will cause the arm to swing forward in engagement with the registering key-bar stud 33 and impart a forward stroke to each key bar 30 associated with a depressed key, the extent of movement of the different key bars depending on the length of the slot 32 in which a depressed key standard is inserted. The movement which is thus communicated to the key bar 30 is communicated to the associate price bar 51 through the connected rocker-arms 61 and 64, or arm 61^a, and the associated price segments 55 of the front ticket stamping set and the rear recording set are accordingly actuated to place in printing relation the numeral thereof corresponding to the numerical designation of the depressed key. During the forward stroke of the cross-bar 14 and after the key bar actuating arms 35 have completed their permissible forward strokes the cross-bar engages the under cam surface of the pair of rocker arms 124 and raises such arms to cause a raising of the V-lock bar 125 carried thereby into locking engagement with the notched edges 127 of the rack-bars 51 to securely lock the previously shifted bars in shifted position so that no movement of the associated price segments will be permitted during the subsequent stamping operation.

During the initial portion of the forward movement of the cross bar the operating bar 163 of the serial numbering mechanisms, which bar has catch engagement around the rear side of the cross bar 14, is permitted to move forward under the action of the spring 167 and actuates the pawls 90 of both serial numbering mechanisms to operate the same to advance the serial number represented by the exposed portions of the printing wheels 81, one unit. When the operating crank 12 and connected cross-bar 14 are near the limit of their forward strokes the forward end of the lever arm 123 strikes the cross-bar 119 and effects a lowering thereof in the frame slots 120, which lowering movement is communicated through the links 118 and pair of rocker arms 116 of the impression pad 115, thereby causing each pad to strike the top of the ticket and effect a printing on its under side through the interposed inking ribbon 108 of the desired data, such, for instance, as the station where the ticket is purchased, the date of purchase, price and serial sales number of the ticket and number of the clerk, as noted on the ticket in Fig. 10. At each forward stroke of the crank arm, unless the interline key is depressed, the rocker arm 156 engages and actuates the catch bar 53 and communicates a forward swinging movement to the impression roll 144 and encircling tape 145 of the recording mechanism into contact with the adjusted price segments and serial number wheels of the rear recording mechanism so that the price and serial sales number of the stamped ticket is recorded on the tape 145. The recording tape 145 is advanced after each printing operation by reason of the forward movement of the push bar 179 by the cross-bar 14 upon the rearward stroke of such cross bar moving the pawl 175 to actuate the tape winding roll 146, the bar 179 having previously moved forward under the action of the spring 182 when the cross bar 14 was advanced.

During the initial portion of the forward movement of the crank-arm 12, the rocker arm 219 (Fig. 13), which moves therewith, permits a forward spring actuated movement of the actuating bar 188 of the inking ribbon mechanisms, which movement of the bar causes a slight feeding of the forward inking ribbon through the interposed mechanism. During the rear stroke of the rocker arm 219, the bar 188 is actuated thereby to return to its normal position and to impart a ribbon feeding movement to the rear inking ribbon through the interposed mechanism.

During the rear stroke of the crank-arm 12 and cross-bar 14, the release finger 234 on the operating shaft 11 at or adjacent to the lower end of the crank arm 12 strikes the registering nose of the release bar 228 (Fig. 2) and effects a raising of such bar to rock the lever 227, shaft 255 carrying the same, and release fingers 226, which latter in turn act on the rearwardly moved lock bars 23 to release the depressed keys 15 and permit their return to normal elevated positions. The rearward rocking of the shaft 11 in returning to its normal position raises the lever arm 123 from the cross-bar 119 to permit a raising of the impression pad 115 under the action of the springs 121. The rearward movement of the cross-bar 14, when the parts are returning to their normal positions, first acts to lower the cam arms 124 and connected V-bar 125 to release the locking engagement of the latter with the rack-bars 51, and the cross-bar 14 then acts against the rocker arms 35 to move them rearward to their normal positions. The rocker-arms 35 during such rearward movements act on the key bars 30 through the springs 36 and studs 33 to draw them rearward to normal positions. The rearward movement of the key bars 30 imparts a return movement to the associated rack-bars 51 and connected price segments 55 through the lever connections 61, 62 and 63. When

the depressed keys are released and spring upward the associated release bars 39, which are held downward by the studs 18 of the depressed keys are permitted to raise to their 5 normal positions and such movement thereof returns the associated catch dogs 42 to their normal positions and the catch lugs 43 of the returning arms 35 are then caused to snap over the catch ends of such dogs into 10 catch engagement therewith.

If it is desired to release the depressed keys 15 before printing a ticket due to the depression of a wrong key or for any other cause, this may be quickly done by depressing 15 the release key 234, which actuates the lever 227 (Fig. 2) and communicates a forward releasing movement to the lock-bars 23 through the shaft 225 and trip arms 226.

If it is desired to print a number of 20 tickets with the same price designation but with successive serial numbers, as where a number of tickets to the same destination are being sold, the repeat key 241 (Fig. 2) is depressed, thereby causing the pin 245 thereon to engage and move the release link 231 and effect a retraction of the nose portion of the release bar 228 from the path of rocking movements of the release finger 234. The repeat key is locked in depressed 25 position by the engagement of the dog 246 with the pin 247. It is thus evident that the crank arm may be repeatedly rocked to operate the ticket printing and recording 30 mechanisms without actuating the release mechanism through the release bar 228. A 35 release of the depressed key is effected by a depression of the release key 234, the plate 239 of which engages and moves the lock dog 246 to disengage its pin 247.

If it is desired to stamp what is known 40 as an interline ticket which requires a number of successive stampings, the operator depresses the interline key 250 (Fig. 2) and the key is locked in depressed position by engagement of the dog 252 with the pin 251. The release bar 228 is also retracted 45 from operating position by reason of the pin 253 on the interline key striking and depressing the release link 231. The depression 50 of the interline key effects a downward rocking of the arm 256 (Figs. 16, 17, 18 and 19) and forward end of the bar 258 to place the cam portion 263 of the finger 260 in the path of movement of the cross-bar 14, so 55 that when such bar is at a predetermined point in its forward movement it engages and effects a raising of the finger 260 so as to lift the pin 265 thereof over the hooked end of the rocker arm 266, whereby the finger 60 is supported in raised position by such arm. By the time the finger 26 has been raised in this manner the actuating bar 163 for the serial numbering mechanisms has moved forward to actuate said mechanisms 65 and to place the pin 264 on said bar over

the rear end of the bar 258 to prevent a raising of the latter bar with the finger 263 through the medium of the spring 262. Upon the return stroke of the cross-bar 14 the feed bar 163 is returned thereby to normal position, thereby retracting the pin 264 from over the bar 258 and permitting a quick raising of the latter bar by the action of the spring 262 to place its rear end in stop relation to the pin 264 so that the serial 70 numbering mechanisms will be prevented from being operated during subsequent operating movements of the machine made for the purpose of repeating the stamping at different places on the interline ticket. The 80 rear end of the bar 258 when raised acts against the bottom edge of the impression roll operating means of the recording mechanism and lifts such bar sufficiently to raise the catch lug 158 thereof above the path of 85 movement of the actuating rocker-arm 156. It is thus evident that during repeated stamping operations the serial numbering mechanisms and the recording mechanism remain inactive. To release the interline key 90 250 from depressed position and the catch arm 266 from supporting engagement with the pin 265 the release key 234 is depressed causing the plate 239 thereof to engage and move the dog 252 to release the pin 251 and 95 also to rock the arm 261 to communicate a forward releasing movement to the catch arm 266.

It is evident that the use of my machine 100 will prevent ticket sellers from defrauding the company for whom they are selling the tickets and particularly from defrauding the purchaser by asking a price for the ticket which is more than the regular price of the same and putting in his pocket the 105 excess amount received. This is a deplorable custom practiced to a considerable extent by clerks selling railroad tickets, as they can very frequently, without the purchaser knowing it, charge a fare in excess of the 110 correct amount and appropriate the excess amount to themselves. With my machine this fraud upon the ticket purchasing public is prevented, or at least reduced to a minimum, by causing the price of each ticket 115 sold to be stamped thereon and the recording feature of the machine furnishes the auditor with an accurate check on each clerk as to the tickets sold by him, the date of sale, and the amount of each sale. The machine also affords protection for the honest clerk, as is apparent.

It will be understood that the particular machine and the different parts thereof illustrated and described are merely a typical 125 embodiment of one form of the invention and that the specific construction described is merely by way of illustration and not by way of limitation or narrowing of the claims, as obviously a great many changes 130

in construction and design can be made without departing from the invention, and, obviously, various of the features described can be omitted leaving the machine still operative to usefully do certain of the work described and such changes are contemplated and would not involve any departure from the invention.

Having thus described our invention, what we claim as new, and desire to secure by Letters Patent, is,—

1. In a machine of the class described, a set of keys selectively movable from normal to operating position, movable means limited as to permissible movement by each key when in operating position and capable of a different predetermined movement for each key, a movable printing element having a different designating mark for each key, means connecting the first means and element for imparting movement from one to the other to place in printing position a designating mark on the element, which mark corresponds to the key disposed in operating position, manually controlled means operable to move the first means, and means automatically operable to lock the first means and element in shifted position during a predetermined portion of the movement of the last means.

2. In a machine of the class described, a set of keys selectively movable from normal to operating position, movable means limited as to permissible movement by each key when in operating position and capable of a different predetermined movement for each key, a movable printing element having a different designating mark for each key, means connecting the first means and element for imparting movement from one to the other to place in printing position a designating mark on the element, which mark corresponds to the key disposed in operating position, manually controlled means operable to move the first means, means for preventing a movement of the first means until one of the keys has been placed in operating position, means operable to lock any key in operative position until the manually controlled means has had a predetermined movement, and means automatically operable to lock the first means and element in shifted position during a predetermined portion of the movement of the manually controlled means.

3. In a machine of the class described, a movable element having different designations thereon successively movable to operative position by movements of the element, means having connection with and operable to move the element, a set of keys selectively operable to coact with a part of said means to limit the permissible movement communicable thereby to the element whereby a movement to operative position of each

designation on the element is controlled by a respective key, manually controlled means operable to move the first means, and means automatically operable to lock the first means and element in shifted position during a predetermined portion of the movement of the last means.

4. In a machine of the class described, a movable element having different designations thereon successively movable to operative position by movements of the element, means having connection with and operable to move the element, a set of keys selectively operable to coact with a part of said means to limit the permissible movement communicable thereby to the element whereby a movement to operative position of each designation on the element is controlled by a respective key, manually controlled means operable to move the first means, means for preventing a movement of the first means until a key has been moved into coacting relation to the first means, and means automatically operable to lock the first means and element in shifted positions during a predetermined portion of the movement of the manually controlled means.

5. In a machine of the class described, a movable element having different designations thereon successively movable to operative position by movements of the element, means having connection with and operable to move the element, a set of keys selectively operable to coact with a part of said means to limit the permissible movement communicable thereby to the element whereby a movement to operative position of each designation on the element is controlled by a respective key, and manually controlled means operable to move the first means, means for preventing a movement of the first means until a key has been moved into coacting relation to the first means, means automatically operable to lock the first means and element in shifted positions during a predetermined portion of the movement of the manually controlled means, and means operable to lock any key in operative position until the manually controlled means has had a predetermined movement.

6. In a machine of the class described, a movable element having different designations thereon movable to operative position by a movement of the element, means having connection with and operable to move the element to place any designation thereon in operative position, said means including a key-bar having notches of different lengths, one notch for each element designation, a set of keys selectively operable to enter respective notches in the key-bar to limit the permissible element actuating movements of the means determined by the length of the engaged notch, manually controlled means operable to move the first means and ele-

ment to place a predetermined element designation in operative position, and means automatically operable to lock the first means and element in shifted positions during a 5 predetermined portion of the movement of the last means.

7. In a machine of the class described, a movable element having different designations thereon movable to operative position by a movement of the element, means having connection with and operable to move the element to place any designation thereon in operative position, said means including a key-bar having notches of different 10 lengths, one notch for each element designation, a set of keys selectively operable to enter respective notches in the key-bar to limit the permissible element actuating movements of the means determined by the 15 length of the engaged notch, manually controlled means operable to move the first means and element to place a predetermined element designation in operative position, means for preventing a movement of the 20 first means until the key has been moved into coacting relation thereto, and means automatically operable to lock the first means and element in shifted positions during a predetermined portion of the 25 movement of the manually controlled means.

8. In a machine of the class described, a movable element having different designations thereon movable to operative position by a movement of the element, means having 30 connection with and operable to move the element to place any designation thereon in operative position, said means including a key-bar having notches of different lengths, one notch for each element designation, a 35 set of keys selectively operable to enter respective notches in the key-bar to limit the permissible element actuating movements of the means determined by the length of the engaged notch, manually controlled means 40 operable to move the first means and element to place a predetermined element designation in operative position, means for preventing a movement of the first means until a key has been moved into coacting relation 45 thereto, and means automatically operable to lock the first means and element in shifted positions during a predetermined portion of the movement of the last means.

9. In a machine of the class described, a printing element mounted for oscillating 50 movements and having different designating marks on its periphery successively movable to operative position by movements of the element, means having operating connection with the element, a key for each element 55 designation operable to engage and limit

the permissible movement of the means to cause a predetermined designation on the element to stop in operative position when the element is moved, manually controlled means operable to impart permissible movement to the first means and element, and means automatically operable to lock any key in operative position when moved to such position and to retain it locked until the last means has had a predetermined 70 movement.

10. In a machine of the class described, a printing element mounted for oscillating movements and having different designating marks on its periphery successively movable to operative position by movements of the elements, means having operating connection with the elements, a key for each element designation operable to engage and limit the permissible movement of the means to cause a predetermined designation on the element to stop in operative position when the element is moved, manually controlled means operable to impart permissible movement to the first means and element, and means for preventing a movement of the first means until a key has been moved into coacting relation thereto. 85

11. In a machine of the class described, a printing element mounted for oscillating 90 movements and having different designating marks on its periphery successively movable to operative position by movements of the element, means having operating connection with the elements, a key for each element designation operable to engage and limit the permissible movement of the means to cause a predetermined designation of the element to stop in operative position when the element is moved, manually controlled means operable to impart permissible movement to the first means and element, and means automatically operable to lock the first means and element in shifted positions during a predetermined portion of the movement of the last means. 100

12. In a machine of the class described, a printing element mounted for oscillating movements and having different designating marks on its periphery successively movable to operative position by movements of the element, means having operating connection with the elements, a key for each element designation operable to engage and limit the permissible movement of the means to cause a predetermined designation on the element to stop in operative position when the element is moved, manually controlled means operable to impart permissible movement to the first means and element, and means for preventing a movement of the first means until a key has been moved into coacting relation thereto, and means automatically operable to lock any key in operative position when moved to such position. 115

- tion and to retain it locked until the manually controlled means has had a predetermined movement.
13. In a machine of the class described, 5 a printing element mounted for oscillating movements and having different designating marks on its periphery successively movable to operative position by movements of the element, means having operating connection with the elements, a key for each element designation operable to engage and limit the permissible movement of the means to cause a predetermined designation on the element to stop in operative position 10
- 15 when the element is moved, manually controlled means operable to impart permissible movement to the first means and element, means for preventing a movement of the first means until a key has been moved 20 into coacting relation thereto, means automatically operable to lock the first means and element in shifted positions during a predetermined portion of the movement of the manually controlled means, and means 25 operable to lock any key in operative position when moved to such position and to retain it so locked until the manually controlled means has had a predetermined movement.
- 30 14. In a machine of the class described, a movable element having different designations thereon successively movable to operative position by a movement of the element, means having connection with and 35 operable to move the element, a set of keys selectively operable to coact with a part of said means to limit the permissible movement communicable thereby to the element whereby a movement to operative position 40 of each designation on the element is controlled by a respective key, a rocker arm normally operable to impart permissible movement to the first means, manually operable means controlling the movement of the 45 rocker arm, means normally locking the rocker arm against movement and released by a movement of any key to operative position.
15. In a machine of the class described, 50 a set of keys, a reciprocally movable key bar having a notch therein for each key whereby a key when moved from normal position enters a respective notch and limits the permissible movement of the bar, the 55 notches being of different predetermined lengths, a second reciprocally movable bar, means for connecting the two bars for communicating movement from one to the other thereof, a member movable by the second 60 bar and having a different designating mark thereon for each key and movable into operative position by a maximum permissible movement of the key bar when a respective key has been moved into its key 65 bar notch, and manually controlled means operable to move the key bar.
16. In a machine of the class described, 70 an oscillating member having different marks successively arranged on its periphery, a rack-bar connected to the member and reciprocally movable to impart oscillating movements thereto, a reciprocally movable key-bar having key engaging notches therein of different lengths, connection between the two bars to communicate reciprocating 75 movements from one to the other, a plurality of keys movable to enter respective key bar notches and then to limit the movement of the key-bar in accordance with the length of the notch, whereby a different predetermined movement is imparted to the 80 rack-bar from a movement of the key-bar for each depressed key, and manually controlled means operable to move the key-bar.
17. In a machine of the class described, 85 a segment, an oscillating member having different marks successively arranged on its periphery, a rack-bar connected to the member and reciprocally movable to impart oscillating movements thereto, a reciprocally 90 movable key-bar having key engaging notches therein of different lengths, connection between the two bars to communicate reciprocating movements from one to the other, a plurality of keys movable to enter a respective key bar notch and then to limit the movement of the key bar in accordance with the length of the notch whereby a different predetermined movement is imparted to the 95 rack-bar from a movement of the key-bar for each depressed key, manually controlled means operable to move the key bar, and means operable to lock any key in depressed position until the last means has had a predetermined movement. 100
18. In a machine of the class described, 105 an oscillating member having different marks successively arranged on its periphery, a rack-bar connected to the member and reciprocally movable to impart oscillating movements thereto, a reciprocally movable key-bar having key engaging notches therein of different lengths, connection between the two bars to communicate reciprocating 110 movements from one to the other, a plurality of keys movable to enter a respective key-bar notch and then to limit the movement of the key-bar in accordance with the length of the notch, whereby a different predetermined movement is imparted to the 115 rack-bar from a movement of the key-bar for each depressed key, manually controlled means operable to move the key-bar, and means for preventing a movement of the part of the last means until one of the keys 120 has been depressed.
19. In a machine of the class described, 125 an oscillating member having different

marks successively arranged on its periphery, a rack-bar connected to the member and reciprocally movable to impart oscillating movements thereto, a reciprocally movable 5 key-bar having key engaging notches therein of different lengths, connection between the two bars to communicate reciprocating movements from one to the other, a plurality of keys movable to enter a respective 10 key-bar notch and then to limit the movement of the key-bar in accordance with the length of the notch whereby a different predetermined movement is imparted to the rack-bar from a movement of the key-bar 15 for each depressed key, manually controlled means operable to move the key-bar, and means automatically operable to lock the rack-bar in shifted position during a predetermined portion of the movement of the 20 last means.

20. In a machine of the class described, a movable price element, a reciprocally movable member, means connecting the member and element and operable to impart movement from one to the other, means including a plurality of keys selectively operable to coact with the member and limit the permissible movement for each key, manually controlled means operable to move the member, and means automatically operable at a 25 predetermined point in a movement of the last means to lock the first means in shifted position.

21. In a machine of the class described, a movable price segment, a reciprocally movable member, means for communicating movements from the member to the segment, a plurality of keys selectively operable to coact with the members to permit a movement thereof whereby the segment is permitted to move a predetermined extent for each depressed key, manually controlled means operable to yieldingly move the member, and means normally operable to lock 40 the member actuating part of the last means in normal position and releasable by the depression of any key.

22. In a machine of the class described, a movable price segment, a reciprocally movable member, means for communicating movements from the member to the segment, a plurality of keys selectively operable to coact with the members to permit a movement thereof whereby the segment is permitted to move a predetermined extent for each depressed key, manually controlled means operable to yieldingly move the member, and means automatically operable to lock the first means in shifted position when 60 the last means has been moved a predetermined extent.

23. In a machine of the class described, a movable price segment, a reciprocally movable rack-bar in operative connection with 65 the segment for rocking the same when the

bar is moved, manually controlled means operable to reciprocate the rack-bar, means having selectively operable parts for coaction with the first means to limit the bar actuating movements a predetermined extent 70 for each selectively operable part, and means operable by the manually controlled means at a predetermined point in its movement to engage the rack-bar and lock it in shifted position. 75

24. In a machine of the class described, a movable price segment, a reciprocally movable rack-bar in operative connection with the segment for rocking the same when the bar is moved, manually controlled means operable to reciprocate the rack-bar, means having selectively operable parts for coaction with the first means to limit the bar actuating movements a predetermined extent 80 for each selectively operable part, means operable by the manually controlled means at a predetermined point in its movement to engage the rack-bar and lock it in shifted position, and means for preventing an operation of the rack-bar by the manually controlled means until the selectively operable second means has been moved to operating position. 85

25. In a machine of the class described, a printing member mounted for rotary reciprocatory movements and having successively disposed peripheral printing designations thereon, means operable to actuate the movements of the member, a plurality of control members selectively operable to coact with the actuating means, each to permit a predetermined member actuating movement thereof to place a certain member designation in printing position, an impression means having an impression part guided for rocking movements with the portions of the member disposed in printing position, said impression means normally standing in inoperative position, means normally operable to permit member actuating movements of the first means and then to impart impression taking movement to the impression means, and means operable by the manually operable means at a predetermined point in its movement to lock the member actuating means in shifted position. 95 100 105 110 115

26. In a machine of the class described, a printing member mounted for rotary reciprocatory movements and having successively disposed peripheral printing designations thereon, means operable to actuate the movements of the member, a plurality of control members selectively operable to coact with the actuating means, each to permit a predetermined member actuating movement thereof to place a certain member designation in printing position, an impression means having an impression part guided for rocking movements with the portions of the member disposed in printing position, said 120 125 130

- impression means normally standing in inoperative position, means normally operable to permit member actuating movements of the first means and then to impart impression taking movement to the impression means, and means normally locking the member actuating means against movement and released by a movement of any control member from normal position.
- 10 27. In a machine of the class described, a printing member having different printing designations thereon and movable to successively place the designations in printing position, actuating means normally movable to actuate the member, key controlled means normally operable to actuate said member to place it in different positions of its movement, an impression means for the member, an inking ribbon between the printing member and impression means, feed means for the inking ribbon and manually operable means for controlling the movements of the member actuating means for actuating the impression means to take an impression and for controlling the ribbon feeding means.
28. In a machine of the class described, a printing member having different printing designations thereon and movable to successively place the designations in printing position, actuating means normally movable to actuate the member, key controlled means normally operable to actuate said member to place it in different positions of its movement, an impression means for the member, an inking ribbon between the printing member and impression means, feed means for the inking ribbon, and manually operable means for actuating the movements of the member actuating means to take an impression and for controlling the ribbon feeding means.
29. In a machine of the class described, two numbering mechanisms, means connecting the said mechanisms for imparting simultaneous operating movements thereto and including a reciprocally movable bar, means normally acting to move the bar in one direction, and manually controlled means operable to permit movements of the bar in one direction and to positively move it in the opposite direction.
30. In a machine of the class described, a stamping member having different stamping designations thereon, key controlled means operable to actuate the member to place a predetermined designation thereon in stamping position, a serial numbering mechanism having number wheels adjacent to the stamping member, and means manually operable to control the movements of the member actuating means and to control the movements of the serial numbering mechanism whereby the number designated by the number wheels is changed for each stamping operation.
31. In a machine of the class described, a printing element having a plurality of printing designations thereon successively movable into printing position by a movement of the element, manually controlled means operable to move the element to place any designation thereof in printing position, a plurality of keys selectively operable to coat with and respectively limit the element actuating movements of said means a predetermined extent for each key, means for locking any key in inoperative position, and means automatically operable at a predetermined point in a movement of the element control means and also manually operable to release the key locking means.
32. In a machine of the class described, a movable element having different printing designations thereon successively movable to printing position by movements of the element, means having connection with and operable to move the element, a set of keys selectively operable to coat with a part of said means to limit the permissible movement communicable thereby to the element whereby a movement to printing position of each designation on the element is controlled by a respective key, manually controlled means operable to move the first means, a serial numbering mechanism having numbering members associated with the printing element, means operable by the control means to actuate the movements of the numbering mechanism, means for locking any key in operative position, means automatically operable by the control means at a predetermined point in its movement to release the key locking means, and means operable to render the release means inoperative so that a releasing movement will not be imparted to the key locking means at each operation of the control means.
33. In a machine of the class described, a movable element having different printing designations thereon successively movable to printing position by movements of the element, means having connection with and operable to move the element, a set of keys selectively operable to coat with a part of said means to limit the permissible movement communicable thereby to the element whereby a movement to printing position of each designation on the element is controlled by a respective key, manually controlled means operable to move the first means, a serial numbering mechanism having numbering members associated with the printing element, means operable by the control means to actuate the movements of the numbering mechanism, means for locking any key in operative position, means automatically operable by the control means at a predetermined point in its movement to release the key locking means, and means operable to render the release means and the

numbering means inoperative during continued operating movements of the control means.

34. In a machine of the class described, a movable element having different printing designations thereon successively movable to printing position by movements of the element, means having connection with and operable to move the element, a set of keys selectively operable to coact with a part of said means to limit the permissible movement communicable thereby to the element whereby a movement to printing position of each designation on the element is controlled by a respective key, manually controlled means operable to move the first means, a serial numbering mechanism having numbering members associated with the printing element, means operable by the control means to actuate the movements of the numbering mechanism, means for locking any key in operative position, means automatically operable by the control means at a predetermined point in its movement to release the key locking means, and means operable to render the release means and the

numbering means inoperative during continued operating movements of the control means, and means operable to release said last means to permit a normal operation of the machine.

35. In a machine of the class described, a key controlled price printing mechanism, manually controlled means for operating said mechanism, means for locking the mechanism in printing position, manually controlled means for imparting printing operations to the mechanism when in locked position, a serial numbering mechanism operable to change its number at each operation of the control means, means normally operable by the control means at each operation thereof to release the printing mechanism locking means, and interline means operable to render the release means inoperative and to prevent an actuating of the numbering mechanism at each operation of the control means.

In testimony whereof we have hereunto signed our names to this specification.

EDWARD B. ROHMER.
LOUIS C. MUELLER.
